ABSTRACT

Disclosed herein is an improvement for a gas turbine which has been adapted to burn fuel processed by catalytic or non catalytic type gas converters. This adaptation has resulted in the reduction of the harmful pollutants being emitted to the environment. The improvement, recognizing that a turbine operating with such processed fuel runs at considerably high combustion chamber temperatures, calls for the positioning of heat exchange mechanisms in the path of the exhaust gases emanating from the turbine's decompression unit. These mechanisms preheat the fuel and air needed in the conversion process. Additionally, heat exchange mechanisms are positioned about and between the reaction chambers in the gas converter. Part of the exhaust gases are routed through these facilitating the gas conversion process. Further, mixing means are provided wherein the preheated air cooperates with the exhaust gases to reduce the heat of the latter before they pass via the turbine's decompression unit into the environment. An alternate improvement calls for the placement of a water vaporizer in the path of the exhaust gases. Water supplied thereto is vaporized and then supplied to the gas converter for reaction with the fuel in a known way.

FIG 1

GAS TURBINE

BACKGROUND OF THE INVENTION

The present invention concerns gas turbines and more particularly turbines wherein there is complete, uniform combustion of the liquid fuel supplied thereto.

The health of the world's population is being endangered more and more by increasing air pollution. This is a particularly serious problem in the thickly settled areas. Exhaust gases not only from motor vehicles with internal-combustion engines, but also those emanating from stationary gas turbines contribute to this pollution problem. This is so primarily because of the non-uniform evaporation and inadequate intermixing of the hydrocarbons and the combustion air, resulting in incomplete combustion. The consequence of this is unburned or at best only partially burned hydrocarbons, carbon monoxide, condensation products, benzpyrenes, tar, soot and aldehydes. These are given off to the air via the exhaust gas.

The harmful secondary effects caused by these exhaust gases can be reduced quite considerably by the use of a gas converter. Such a converter is described in the German Offenlegungsschrift 2,103,008, German Offenlegungsschrift 2,135,650 which was not prepublished and U.S. pat. application, Ser. No. 372,422. In these gas converters, the fuel containing liquid hydrocarbons is first evaporated, vaporized or atomized, and the gaseous or vaporous fuel thus obtained is conducted over a catalyst for conversion into a gas mixture. This latter mixture, so-called reformed gas, contains carbon monoxide, carbon dioxide, methane and/or hydrogen. The conversion of the fuel into the reformed gas can be made relatively soot free by feeding back a portion of the exhaust gas from the combustion chamber of the engine fed with the reformed gas and mixing this exhaust gas with an oxygen-carrying gas such as air and passing this mixture together with the fuel through the converter.

The gas converter employs perforated, sintered blocks having a multiplicity of closely spaced passage holes. They may be of a non-catalytic type as described in the German Offenlegungsschrift 2,132,819 or they can be of the catalytic type such as described in greater detail in the German Offenlegungsschrift 1,939,535. Where the catalytic type sintered blocks are employed, catalytic conversion of the hydrocarbons is obtained.

As noted above, stationary gas turbines are also large polluters of the environment. It has been recognized that a suitable way of materially reducing the emission of harmful pollutants by the gas turbines is an arrangement employing the gas converter described in the preceding patent applications, in a suitable fashion wherein the reformed gas generated by the converter becomes the fuel for the gas turbines.

A gas turbine usually consists of a compressor for the air required for combustion, a combustion chamber and a decompression turbine. The amount of air required for the combustion process in the gas turbine, including the excess air required for maintaining the maximum combustion temperature, is provided by the compressor.

A gas turbine operated with such reformed gases and compressed air can be run at considerably high combustion chamber temperatures than the conventional gas turbines. Therefore, the temperature of the exhaust gases entering the decompression turbine from the

combustion chamber and discharging from the decompression turbine is higher also.

It is therefore an object of this invention to combine a suitable gas converter with said gas turbines to substantially reduce the concentration of harmful components and in the turbine's exhaust gas.

It is another object of this invention to provide an improved gas turbine which is supplied fuel gases from the gas converter thereby achieving complete and uniform combustion.

It is still another object of this invention to provide a gas turbine which is more efficient than prior art turbines in that exhaust gas heat is recycled through the system prior to discharge into the environment to preheat the fuel and air before they pass through the gas converter and combustion chamber respectively.

SUMMARY OF THE INVENTION

In satisfaction of these objects and of others more readily apparent with a reading of the hereinafter disclosed invention, an improved gas turbine is provided which employs as its fuel the reformed gas product of a gas converter. The compressed air required for combustion is preheated in a suitably arranged heat exchanger by the exhaust gases. The liquid fuel which is processed and converted to the reformed gas by the gas converter is also preheated and vaporized by the heat of the exhaust gases in a suitable exchanger. Finally, the conversion of the vaporized liquid fuel into the reformed gas by the gas converter is facilitated by the provision of heat exchangers surrounding and interposed between the reaction chambers of the converter. Part of the heat of the exhaust gases is given up to the conversion process through these exchangers.

Due to the combination of exhaust gas heat utilization and higher combustion temperatures in the arrangement according to the invention, a particularly great increase in the efficiency is obtained, so that an overall efficiency of more than 40 percent can be achieved. Mixing means are also provided for cooling the exhaust gases resulting in a temperature compatible with the decompression turbine design. Further, in yet another embodiment of this invention, a steam generator is placed in the path of the exhaust gases exiting from the decompression turbine. Water is converted to water vapor, which is in turn supplied to the gas converter where it reacts with the preheated fuel instead of the exhaust gases to achieve conversion of the vaporized fuel to the so-called reformed gas.

BRIEF DESCRIPTION OF THE DRAWINGS

FIG. 1 is a schematic representation of the subject invention.

DESCRIPTION OF THE PREFERRED EMBODIMENT

Referring to FIG. 1 there is shown the basic elements of a well-known gas turbine including a compressor unit 1, a decompression turbine 4, and a combustion chamber 3. The standard gas turbine is modified to include a gas converter 2 which processes the fuel supplied thereto through line 9 to thereby provide a so-called reformed gas in accordance with the aforementioned patent applications. This becomes the fuel for combustion chamber 3.

The compressor 1 draws in air, symbolically represented by line 30. It compresses the air required for

combustion and routes that compressed air to the remainder of the system through line 8. The compressor and decompression turbine 4 are shown connected together by line 31, which represents the common shaft upon which both would rotate in a standard turbine design.

The compressed air passing through line 8 next proceeds through heat exchanger 6. The air exiting from heat exchanger 6 is heated by its passage therethrough in a manner soon to be described. It exits the exchanger 6 via duct 32 at which point it splits, a portion thereof being supplied to a mixing chamber 7 and yet another portion thereof being supplied along line 8' to combustion chamber 3.

The liquid fuel is supplied to heat exchanger 5 via 15 duct 33. The fuel is vaporized in the heat exchanger and is supplied to gas converter 2 through a suitable line, 9.

The combustion chamber 3 and the converter 2 are interconnected. Part of the exhaust gases of combustion chamber 3 is supplied to one input of the gas converter 2 by way of line 22, while the output of the gas converter 2 is supplied as the second input to the combustion chamber 3 via duct 10.

The remainder of the exhaust gas, is supplied via lines 25 34, 35, 36, 37 and 38 to suitable heat exchange mechanisms within the gas converter itself. Such mechanisms are represented by reference numerals 14, 15, 16, 17 and 18. Although it need not be, gas converter 2 is preferably of the multi-stage design with a plurality of reaction chambers such as 19, 20 and 21. Heat exchange mechanisms 14, 15 and 16 surround the reaction chambers 19, 20 and 21 while exchangers 17 and 18 are interposed between 19 and 20, and 20 and 21, respectively. The part of the exhaust gases that go through the heat exchangers 14, 15, 16, 17 and 18 gives off heat energy to the gas mixture flowing through the converter. This facilitates the conversion of the vaporized fuel in line 9 to the reformed gas supplied to the combustion chamber. The exhaust gases exit from heat exchangers 40 14, 17, 15, 18 and 16 via ducts 34', 35', 36', 37' and 38' respectively. These are combined through a suitable manifold arrangement and supplied by way of line 23 to mixing chamber 7.

Mixing chamber 7, as noted earlier, is also supplied by the compressed air exiting from heat exchanger 6. Although preheated, this air is less than the temperature of the exhaust gases in line 23. Within mixing chamber 7, the compressed air exiting from heat exchanger 6 extracts some of the heat from the exhaust 50 gases in line 23. The exhaust gases, reduced in temperature, are supplied to the decompression turbine 4 via line 11.

The decompression turbine directs the exhaust gases, 55 exiting therefrom by line 12 through the heat exchange devices 6 and 5. As they pass through the exchangers, the exhaust gases preheat both the air and the liquid fuel prior to their use in the remainder or balance of the system.

Once past the heat exchangers 6 and 5, the exhaust 60 gas exits to the outside environment via duct or exhaust pipe 12'.

In an alternate embodiment of the subject invention, a steam generator 24, shown in phantom may be inserted in the path of the exhaust gases emanating from the decompression turbine. Water is supplied thereto by line 39. The heat of the exhaust gases converts the

water to steam, which is then routed to the gas converter 2 through line 25. In this arrangement the exhaust gas fed to the converter 2 is completely or partially replaced (through suitable valving, not shown) by the steam, which thereafter reacts with the fuel in a well-known conversion process.

It can also be appreciated that changes in the above embodiment can be made without departing from the scope of the present invention, and that other variations of the specific arrangement disclosed above, can be made by those skilled in the art without departing from the invention as defined in the appended claims.

What is claimed is:

1. In combination with a gas turbine having a compressor, a combustion chamber, a gas converter and a decompression turbine for complete and uniform combustion of the liquid fuel supplied thereto, the improvement which comprises:

a. a first heat exchange means positioned in the path of the exhaust gases emanating from said decompression turbine, said first heat exchange means adapted to receive the air exiting from said compressor, said compressed air being heated by the exhaust gases passing through said first heat exchange means;

b. means for supplying said heated compressed air to said combustion chamber;

c. a second heat exchange means positioned in the path of the exhaust gases emanating from said decompression turbine, said second heat exchange means adapted to receive said liquid fuel, said liquid fuel being vaporized by the heat of the exhaust gases passing through said second heat exchange means;

d. means for connecting said second heat exchange means to said gas converter for supplying said vaporized liquid fuel to said gas converter; and

e. a gas converter comprising:

1. a plurality of reaction chambers;

2. heat exchange means in working relationship with each of said reaction chambers;

3. heat exchange means interposed between said reaction chambers; and

4. means for conducting a portion of the exhaust gases from said combustion chamber to each of said heat exchange mechanisms in said gas converter, whereby the heat of said exhaust gases given off in the gas converter heat exchange means facilitates the gas conversion process.

2. The improved gas turbine of claim 1 further comprising:

a. a mixing chamber;

b. means for supplying a part of said heated compressed air to said mixing chamber;

c. means for routing the exhaust gases conducted to said heat exchange mechanisms in said gas converter, after passing through said latter heat exchange mechanisms, to said mixing chamber, said mixing chamber adapted such that the heated, compressed air flowing in said supply means cooperates with the exhaust gases routed to the mixing chamber to thereby cool said exhaust gases; and

d. means for connecting said mixing chamber to said decompression turbine, said latter connecting means transferring said cooled exhaust gases to said decompression turbine.

3. The improved gas turbine of claim 2 further comprising:

- a. means for vaporizing water, positioned in the path of the exhaust gases emanating from said decompression turbine;
- b. means for supplying water to said vaporizing means; and
- c. means for connecting said vaporizing means to said gas converter to thereby supply said gas converter with vaporized water for reaction with said vaporized liquid fuel.

4. The improved gas turbine of claim 1 further comprising:

- a. means for vaporizing water, positioned in the path

of the exhaust gases emanating from said decompression turbine;

- b. means for supplying water to said vaporizing means; and
- c. means for connecting said vaporizing means to said gas converter to thereby supply said gas converter with vaporized water for reaction with said vaporized liquid fuel.

5. The improved gas turbine of claim 1 further comprising means for conducting a further portion of the exhaust gases from said combustion chamber to said plurality of reaction chambers.
